UNITED STATES PATENT OFFICE

2,609,416

ELECTRIC CONNECTOR

Harry D. Cousins, Chicago, Ill.

Application April 28, 1951, Serial No. 223,619

2 Claims. (Cl. 173—361)

1

This invention relates to electric connectors and more specifically to that part of the connector commonly referred to as the "plug" and which is adapted to be detachably connected to the other part of the connector commonly referred to as the "socket."

An object of my invention is to provide a plug of the character hereinafter described having a minimum number of parts in which the conductor wires are securely connected to the prongs of the plug without the employment of solder, screws or the like.

Another object of the invention is to provide in a plug of the character hereinafter described a novel arrangement for securely connecting the conductor wires to the prongs of the plug in a manner such that the wires can not be easily disconnected from the prongs and one wherein such wires are securely connected to the prongs by a simple operation without the employment of the usual tools for such purpose.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention;

Fig. 2 is a sectional detail view taken substantially on line 2—2 of Fig. 3;

Fig. 3 is a sectional detail view taken substantially on line 3—3 of Fig. 2;

Fig. 4 is a perspective view of one of the prongs;

Fig. 5 is a sectional detail view similar to Fig. 3 but showing certain parts in different positions; and

Fig. 6 is a sectional detail view similar to Fig. 5 but showing certain parts thereof in different positions.

The plug comprising my invention is shown in its preferred form of construction in the accompanying drawings. In this connection the plug comprises a body 10 which may be molded in a single operation from suitable insulating material or, if desired, in two similar half sections. In the latter case, the sections are secured together by a suitable adhesive material. In either case the plug 10 at its outer end portion 11 provides a counterbore 12 preferably of a diameter slightly larger than the diameter of an electric cord 13 and of a depth to permit the end portion 14 of such cord to be projected a substantial distance into the bore 12 for safety purposes. This cord 13 comprises two conductor wires 15 bound

and insulated from each other in a well-known manner. In the present instance these wires are each made up of a plurality of fine wire strands.

The interior of the body 10 is provided with 5 parallel passages 16 separated from each other by a central web 17. These passages 16 communicate with the bore and are adapted to have projected therein the end portions 18 of the wires 15.

The end portions 19 of the passage 16 curve 10 outwardly from each other and traverse spaced slots 20 formed in the body 10. These slots 20 extend in a direction parallel with the long axis of the plug and are adapted to have projected therein the shanks 21 of prongs 22. Each of 15 these prongs 22 is provided with an elongated slot 23. The end portion 24 of the slot 23 is shaped to conform to the cross-sectional shape and size of the end portions 19 of the passages 16 and to register therewith. Opposite this end 20 portion 24 the prong provides a finger 25 substantially triangular in plan view, with its apex directed in the direction toward the end portion 24 of the slot 23.

Each of the prongs 22 at its end portion opposite the slot 23 is turned back upon itself to provide a yieldable latching finger 26. These prongs are formed of conductive spring material.

Prior to the connection of the prongs to the 30 wire end portions 18 the prongs are projected in the slots 20 so as to bring the end portions 24 of the slots 23 in registration with the end portions of the passages 16. The wire lengths are then fed into the passages to project their end portions 20' through the end portions 24 of the 35 slots 23. Upon this accomplishment, the prongs are then moved outwardly from the plug body 10 to penetrate the fingers 25 into the wire end portions 20' and to press the wire end portions 20' against adjacent walls of the passage portions 19.

40 After this operation has been accomplished, the latching fingers 26 are flexed toward the shanks of the prongs 22 to latch their end portions 27 to the rear of keeper beads 28, thereby to securely latch the prongs in position upon the plug body 10 with the fingers 25 securely connecting the wires 15 to the prongs.

From this description it is apparent that my 50 improved plug may be assembled by one other than a skilled mechanic and with ease and the minimum amount of labor. Should it be desired to replace the wires 15, such wires may be disconnected from the prongs and replacement. Wires can be connected to the respective prongs by carrying out the simple operation hereinbefore set forth.

My improved plug may be manufactured at an economical cost and may be manufactured of such material as will best serve the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An electric plug comprising a body having formed in one end portion a counterbore into which an end portion of an electric cord having two conductor wires is projected, said body having spaced passages formed therein with corresponding end portions of the passages communicating with the counterbore and with opposite end portions of the passages curved in an outward direction with respect to each other, said body having spaced slots formed therein in the direction of its long axis extending beyond and bisecting the curved end portions of said passages, a pair of prongs having shank portions projected into said slots, each of said shank portions having an elongated slot formed therein with one end portion of the slot formed to register with the curved portion of the passage when said shank is projected the depth of the first-mentioned slots and having at the end opposite thereof a penetrating finger adapted to penetrate a wire length positioned in an adjacent curved passage, said shank portions each having an integral yieldable latching finger, and keeper beads formed on said plug adjacent said shank receiving slots and adapted to be engaged by said latching fingers to secure said fingers in close parallel relation with respect to said shanks and to latch said prongs in wire penetrating position with respect to said wire lengths.

2. An electric plug comprising a body having formed in one end portion a counterbore into which an end portion of an electric cord having two conductor wires is projected, said body having spaced passages formed therein with corresponding end portions of the passages communicating with the counterbore and with opposite end portions of the passages curved in an outward direction with respect to each other, said passages being separated by a web provided within said body, said body having spaced slots formed therein in the direction of its long axis extending beyond and bisecting the curved end portions of said passages, a pair of prongs having shank portions of a length less than the depth of the slots and adapted to be slidably projected into said slots, each of said shank portions having an elongated slot formed therein with one end portion of the slot formed to register with the curved portion of the passage when said shank is projected the length of the first-mentioned slots and having at the end opposite thereof a penetrating finger adapted to penetrate a wire length positioned in an adjacent curved passage, said shank portions each having an integral yieldable latching finger, and keeper beads formed on said plug adjacent said shank receiving slots and adapted to be engaged by said latching fingers to secure said fingers in close parallel relation with respect to said shanks and to latch said prongs in wire penetrating position with respect to said wire lengths.

HARRY D. COUSINS.
